UNITED STATES PATENT OFFICE

156,790

AIR REGISTER GRILLE PLATE OR SIMILAR ARTICLE

Arthur C. Wesche, Bridgeport, Conn., assignor to General Electric Company, a corporation of
New York

Application February 19, 1949, Serial No. 951

Term of patent 14 years

(Cl. D62—4)

To all whom it may concern:

Be it known that I, Arthur C. Wesche, a citizen of the United States, residing at Bridgeport, in the county of Fairfield, State of Connecticut, have invented a new, original, and ornamental Design for an Air Register Grille Plate or Similar Article, of which the following is a specification, reference being had to the accompanying drawing, forming a part thereof.

The single figure of the drawing is a perspective view of an air register grille plate or similar article, embodying my new design.

I claim:

The ornamental design for an air register grille plate or similar article, substantially as shown.

ARTHUR C. WESCHE.
